UNITED STATES PATENT OFFICE.

MICHAEL BURKE, OF MOUNT PLEASANT, IOWA.

DERRICK.

1,396,250.

Specification of Letters Patent. Patented Nov. 8, 1921.

Application filed November 1, 1920. Serial No. 421,071.

To all whom it may concern:

Be it known that I, MICHAEL BURKE, a citizen of the United States, residing at Mount Pleasant, in the county of Henry and State of Iowa, have invented certain new and useful Improvements in Derricks; and I do declare the following to be a full, clear, and exact description of the invention, such as will enable others skilled in the art to 10 which it appertains to make and use the same.

This invention relates to improvements in derricks, and has particular reference to a device of this class which is especially, 15 although not necessarily, designed for hoisting hay and the like.

The principal object of the invention is to provide a device of the above mentioned type embodying a base, and a standard rising 20 from this base, this standard carrying a pivotally mounted boom and this boom being elevated in a step-by-step manner by novel elevating mechanism which is manually operated and is such that it retains the 25 boom in each higher elevated position to which it is moved.

Another object of the invention is to provide a derrick embodying the above construction together with means for elevating 30 the boom independent of the above referred to hoisting means, this elevating means serving to disengage the boom from the hoisting lever so that the boom may be easily and readily returned to its normal position.

35 Other objects and advantages of the invention will be apparent during the course of the following description.

In the accompanying drawings forming a part of this specification and in which like 40 numerals are employed to designate like parts throughout the same:

Figure 1 is a side elevation of a derrick constructed in accordance with my invention.

45 Fig. 2 is an end elevation with the boom shown in section.

Fig. 3 is a sectional view taken on the plane of the line 3—3 of Fig. 1, looking in the direction of the arrows.

50 Fig. 4 is a detail view, partly in section, of the lower portion of the derrick, showing the manner in which the standard is connected to the base.

Fig. 5 is a detail section taken on the plane 55 of the line 5—5 of Fig. 1.

Referring to the drawings, wherein the preferred embodiment of my invention is clearly illustrated, it will be seen that the numeral 1 designates a base, which may be of any suitable construction, while the 60 numeral 2 designates a standard which rises from this base and supports the novel boom and hoisting mechanism to be hereinafter specifically described. It is desirable to mount the standard for rotation on the base 65 so that the load may be connected to the boom at any suitable point and conveniently carried to the desired place of deposit. The standard may be rotatably connected to the base in any suitable way, such as for 70 instance, as shown in Fig. 4. By reference to this figure, it will be seen that the base is provided with an aperture and the standard carries a removable headed member which passes through and is rotatable in this 75 aperture. For the purpose of increasing the rigidity of the device, I will employ a plurality of braces 4 which are connected at their lower ends to the base and at their upper ends to a collar 5 through which the 80 standard extends and in which it is rotatable.

As before intimated, my derrick includes a boom 6 which is connected to the standard by means of a quickly detachable clamp 85 7. This boom in its preferred form is provided on its underface with a plurality of closely spaced shoulders between which are cam surfaces, this construction constituting a plurality of ratchet teeth 8. A hoisting 90 lever 9 is pivoted at its lower end in the clamp 10 and this lever is provided at its upper end with a T-head 11 which is adapted to engage said teeth and elevate the boom in a step-by-step manner and retain it in each 95 higher position to which it has been moved when movement is imparted to it by means of the manually operated cable 12. This cable is connected to an extension 13 connected to the T-head 11 and passing through 100 a slot in the boom 6. An eye or pulley 14 is arranged on the standard and the cable is permitted to pass through it and downwardly to a point near the base, where it is adapted to be wound around a cleat 15 or 105 other similar retaining device. It is obvious that with this construction, by pulling downwardly on the rope or cable 12, movement will be imparted to the lever 9 and that since this lever is engageable with the teeth 110

8, it will elevate the boom in a step-by-step manner and will automatically lock it in each higher position to which it has been moved, thus enabling a single person to very 5 easily elevate the boom with the slightest possible exertion.

While any other means may be employed for disengaging the boom from the hoisting lever, I prefer to make use of the extremely 10 simple means consisting of a cable or rope 16, which is connected to the outer end of the boom, passes through the pulley 17 on the standard and passes downwardly along the latter and is connected to one of the 15 cleats 15. In practical use, a fork or block and tackle will be connected to the boom through the medium of the short cable 18. Furthermore, in order to prevent the base 20 from moving, it is provided at its corners with eyes 19 through which stakes can be driven for the purpose of retaining it stationary.

In all probability, persons skilled in the art to which this invention relates will be 25 enabled to obtain a clear understanding of the invention from the foregoing description taken in connection with the drawings. However, it may be advisable to review the 30 operation of the device very briefly. It is as follows: The hay or other article to be elevated and carried to a suitable place of deposit, is connected to the depending cable 18 by a suitable release fork or the like and it is elevated in a step-by-step manner by 35 simply pulling downward on the cable 12. Such pulling of this cable will impart movement to the hoisting lever 9 and due to its engagement with the teeth 8, the boom will be elevated in the above set forth manner 40 and will be retained in each position to which it has been moved by this lever. When the load has been raised to the desired elevation, the standard may be rotated and the load dropped at the suitable place of 45 deposit. In order to permit the boom to return to its normal position, it is only necessary to catch hold of the cable 16 and pull it downwardly, which will cause the boom to be elevated and disengaged from the 50 hoisting lever 9, the latter automatically moving to its normal position by reason of its own weight. Effective engagement of the hoisting lever with the teeth 8 is insured because of the fact that this lever carries 55 an extension which passes through the slot in the boom. Thus, the lever is at all times in the proper position for effective operation.

With a device of the construction described, 60 it will be seen that a single person may conveniently hoist hay or any other article and move it to the desired point of deposit. Thus, unnecessary labor can be dispensed with. The operator need not be placed under unnecessary strain in elevating the boom,

because by exerting a rather hard pull on the cable 12, he can gradually elevate this boom and it will be locked in each higher position to which it has been moved. These, and other advantages and features of my 70 derrick have, no doubt, become apparent to the reader.

Since probably the best results may be obtained with the construction and arrangement shown and described, this construction 75 and arrangement is taken as the preferred embodiment of my invention. However, I wish it to be understood that various minor changes in the shape, size, and arrangement of parts may be resorted to without departing 80 from the spirit of the invention or the scope of the subjoined claims.

I claim:

1. In a derrick, a base, a standard rising therefrom, a gravity lowered boom pivotally mounted on said standard, a hoisting cable for elevating said boom, and a separate and independent means for elevating the boom in step by step manner and holding it in the various positions to which it has been moved, 90 said cable serving to disengage said boom from the means when desired to restore the boom to its normal position.

2. In a derrick, a base, a standard rising therefrom, a gravity lowered boom pivotally mounted on said standard, a hoisting cable for elevating said boom, and a separate and independent manually hoisted and gravity lowered lever pivoted on said standard and slidably engaged at its upper end with said boom for elevating the latter in step by step manner and holding it in the various positions taken, the aforesaid cable serving to disengage the boom from the lever to permit the latter to resume its normal position. 100

3. In a derrick, a base, a standard rising therefrom, a boom pivoted on the standard and provided with shoulders, a hoisting lever pivoted on said standard having a head at its upper end for successively engaging said shoulders and elevating the boom in a step-by-step manner and retaining it in each higher position to which it has been moved, 110 and means for actuating said lever.

4. The structure set forth in claim 3, together with additional and separate means for elevating the boom and disengaging it from said hoisting lever, permitting the boom to be lowered by gravity. 115

5. In a derrick, a base, a standard rising therefrom, a boom pivotally mounted on the standard and provided on its under face with spaced shoulders and cam surfaces between said shoulders, a hoisting lever also pivoted on the standard, being slidably connected with the boom at its upper end and having an integral head at this end for engaging said shoulders and riding on said cam surfaces for moving the boom upwardly in a step by step manner, actuating means 125 130

for said lever, and means for disengaging said boom from said head to permit lowering of the boom.

6. In a derrick, a base, a standard rising 5 therefrom, a boom pivotally mounted on this standard, being provided with a slot, and being also provided on its underface with ratchet teeth, a hoisting lever also pivoted to the standard and having a head at its outer

end for coöperation with said teeth, being 10 also provided with a portion extending through said slot, a pull-cable connected to said portion for actuating the lever, and another cable connected to the boom for disengaging it from the lever.

In testimony whereof I have hereunto set 15 my hand.

MICHAEL BURKE.
